UNITED STATES PATENT OFFICE.

ISRAEL I. ZIPERSTEIN, OF CHICAGO, ILLINOIS, ASSIGNOR OF TWENTY PER CENT TO JULIUS B. RUBENSTEIN AND FIVE PER CENT TO JACOB S. GUTHMAN.

AERONAUTICAL DEVICE.

Application filed April 8, 1922. Serial No. 550,099.

To all whom it may concern:

Be it known that I, ISRAEL I. ZIPERSTEIN, a citizen of Poland, residing at Chicago, county of Cook, and State of Illinois, have invented a new and useful Improvement in Aeronautical Devices, of which the following is a specification.

This invention relates to aeronautical devices, and more particularly pertains to an improved composite device for elevating and propelling so-called heavier-than-air machines; but, while this invention is illustrated as employed in itself for propelling and elevating purposes, it will be observed, that the device may be employed as a stabilizing device for airplanes and dirigible balloons, and thus this invention finds a wide field of utility for many similar purposes.

The principal objects and advantages which characterize this invention reside in: the provision of improved means for propelling, elevating and stabilizing an aeronautical carrier, such as commonly called flying machines; the provision of improved means for elevating and propelling a carrier; the provision of improved safety means in conjunction with and forming a part of the propelling and elevating means; the provision of improved gravity negative means for setting up a pressure to elevate and sustain a carrier, the propelling means cooperating with said elevating means; the provision of improved steering means; the provision of an elevating and sustaining means cooperating with propelling means for causing a supporting carrier to be raised and sustained as well as propelled in a desired plane; and the combination of the foregoing features and elements in a light, strong and durable, and efficient structure for the purposes set forth.

This invention is further characterized by an improved unit structure embodying propelling and cooperating elevating means capable of installation upon a standard heavier-than-air machine or on a dirigible balloon for propelling and stabilizing purposes. This invention further contemplates an improved arrangement of the planes, of an aeroplane or other heavier-than-air machine, or the combination of such an arrangement with a dirigible balloon, whereby to in effect obtain the function of a para-

chute, and thereby afford a feature of 55 safety.

The foregoing and such other objects and advantages as may appear or be pointed out as this description proceeds are attained in the several structural embodiments illustrated in the accompanying drawings, wherein:

Figure 1 is a perspective view of a heavier-than-air flying machine embodying the improvements of this invention. 65

Figure 2 is a fragmentary side elevational view of the same.

Figure 3 is a fragmentary top plan of the device illustrated in Figures 1 and 2, parts thereof being in section. 70

Figure 4 is a fragmentary longitudinal sectional view taken on the line 4—4 of Fig. 3, looking in the direction indicated by the arrows.

Figure 5 is an enlarged transverse sectional view taken on line 5—5 of Figure 3, looking in the direction indicated by the arrows. 75

Figure 6 is an enlarged fragmentary sectional perspective view of one of the rotatable planes. 80

Figure 7 is an enlarged fragmentary sectional view of one of the rotatable planes.

Figure 8 is an enlarged fragmentary elevational view of a connecting element. 85

Figure 9 is an enlarged sectional view taken on line 9—9 of Figure 8, looking in the direction indicated by the arrows.

Figure 10 is an enlarged fragmentary sectional view of the propelling and stabilizing frame. 90

Figure 11 is an enlarged fragmentary elevational view of a detail.

Figure 12 is an enlarged transverse sectional view taken on line 12—12 of Figure 10, looking in the direction indicated by the arrows. 95

Figure 13 is a perspective view of a seaplane, illustrating another application of this invention. 100

Figure 14 is a top plan of a dirigible balloon illustrating a further application of this invention.

Figure 15 is a side elevational view of the same. 105

Referring more particularly to the drawing, and first to Figures 1 to 4, inclusive, this invention embodies a carriage A, here

illustrated as embodying a frame similar to a bicycle frame, although any other desired form might be employed, this frame having a driving wheel 5 which may be manually operated by the operator in the usual well-known way, so that the device may be moved from place to place on the ground. The device is also provided with a steering wheel 6, manipulated by the handle-bar 7, the 10 wheel 6 having a disk 8 thereon, so that this wheel may serve as a rudder when the device is in the air. A pair of small wheels 9 are journaled on the free ends of the brace rods 10, which latter extend from the rear 15 portion of the frame or carrier A, said wheels 9 serving to support the whole device upright when on the ground. A pilot's seat 11 is provided over the rear end of the carriage for supporting the pilot in a convenient position to manipulate the handle-bars, and other mechanism.

Pedals 12—12 may serve to drive the device when in the air or on the ground, the connection between the pedals and driving 25 wheel 5 being omitted. A second pair of pedals 13 are provided, these latter pedals being connected by links 14—14 to levers 15—15, which latter are fixedly connected to the elevating and depressing rudder 16, 30 said rudder being pivoted at 17 on the rear end of the carriage A.

The carriage A, to the rear of the seat 11, is provided with rectangular horizontal bracket frame 18, said frame having stirrups 19—35 19 for supporting a source of power, such as an internal combustion engine 20. The foregoing elements described complete the carrying part of the device, and may, of course, be substituted with other supporting, driving and controlling means, such as the standard aeroplane fuselage.

The aeronautical propelling and sustaining mechanisms, also employed for elevating the device into the air, are supported by 45 the frame A, from which mechanisms the frame A and its parts are suspended when the device is in flight.

In order to support the propelling and other associated mechanism, I provide a 50 box-like structure 21, open at its forward and rear ends, so that a fore and aft or longitudinal passageway 22 is provided for permitting the passage of air therethrough with the least resistance. This structure 21 is provided with a top wall 23 and side walls 55 24 and 25, which latter support the mechanisms referred to hereinbefore and of which there are here shown two, designated B and C. Of course, additional pairs of these devices may be provided as the occasion may demand, the two shown being sufficient for the purpose. The structure 21 is connected to the frame or carriage A by divergent struts 26—26, at the forward part, and by vertical struts 27—27 at the rear part, the

struts 26 being clamped at 28 to the frame A, and the struts 27 being connected in a suitable manner to the sides of the bracket frame 18. Transverse braces 29—29 extend across the bottom of the structure 21 so as to make the same more rigid.

The elevating and propelling mechanism includes the two units B and C, and as these elements are substantially identical in construction a description of but one will suffice. Referring to the element C, shown in its entirety in Figures 1 to 4, inclusive, there are provided two triangular end brackets 30 and 31, composed of the vertical straps 32 and 33 and the converging straps 34, are secured to the side wall 25. The straps 34 support bearing elements 35 and 36, the straps 34 being preferably integral and extending about the bearing elements, as indicated at 37 in Figures 4 and 11. Rods 38 and 39 extend from bracket bearings 40 and 41, respectively, which bracket members are secured to the straps 32 and 33, to the bearings 35 and 36.

The bearings 35 and 36 support non-rotatively a longitudinal shaft 42, said shaft having mounted thereon a pair of truss frames F and F', the shaft passing through the medial portion of said frames. The free ends of said truss frames support the elevating devices E—E, these devices being substantially semi-cylindrical and embodying a construction to be described presently. The shaft 42, near its opposite ends, and outside of the elevating devices, supports fore and aft propellers 43 and 44, respectively, said propellers having their respective blades at ninety degrees, as best seen in Figure 4. The propellers, however, are supported within the end brackets 30 and 31. The bearings 35 and 36 support each a sprocket, said sprockets being designated 45—45 and having each a driving chain 46 trained thereover, said chain also being trained over a sprocket 47 mounted in the bearing brackets 40 and 41, there being one of the sprockets 47 in each of said bearing brackets. As the bearing devices 35 and 36, propellers, bearing devices 40 and 41, and the frames F and F' are substantial duplicates and arranged on the front and rear ends of the machine, a description of one of each of the same will suffice.

As seen in Figures 8 to 12, inclusive, the parts last referred to above appear in detail, the bearing 35 being composed of the spaced plates 48—48 riveted at 49—49 to the adjacent portion of the braces 34, each of said plates 48 being provided with complementary ears 50—50 and 51—51, transverse studs 52 and 53 being riveted in the lugs 50 and 51, respectively, and extending through openings in the ears 50 and 51 on the opposite plate, the ends of said studs being threaded to receive retaining nuts.

54—54. The plates 48—48 are provided with concentric openings 55 and 56 for receiving bearing bushings 57—57, the bushings in the opening 56 being of greater diameter than that in the opening 55. The stud 53 serves to receive and hold an eye 58 threaded at 59 to the outer end of the brace rod 38.

A supporting housing 60, which may be either cylindrical or provided with a polygonal external surface, is mounted upon a shaft 42, said housing having one end reduced at 61 to engage the bushing 57 and squared at 62 to receive the sprocket 45, which latter is complementally provided with a central opening for this purpose. The housing, beyond the squared portion 62, is further reduced to engage the bushing 55, and an annular space is afforded between the cover-plate 63 and the reduced end of the housing for accommodating an annular flange 64 formed on the outer enlarged portion 65 of the shaft 42, a reduced threaded stud 66 extending through the cover-plate 63 to receive a retaining nut 67. The plate 63 is secured to the outer bearing plate 48 by a pair of screws 68.

The housing 60 is provided with a longitudinal chamber 69 carrying ball-races 70 and 71, a sleeve 72 being snugly engaged with the enlarged portion 65 of the stationary shaft and serving to retain the inner races 73 and 74, balls 75 and 76 being interposed between the races 70 and 73 and the races 71 and 74, respectively. The enlarged shaft portion 65 is threaded near its inner end to receive a retaining nut 77 and an annular ring 78 is threaded into the housing 60 to retain the bearing race 71. The enlarged shaft portion 65 is reduced to the size of the shaft 42 at 79, and to said part 79 is secured a hub 80 carrying, at either end, a pair of sprockets 81, said hub and sprockets being fixed to the part 79 by means of a transverse pin 82. The shaft portion 79 is reduced and received into the shaft 42, a transverse pin 83 serving to fixedly connect the portion 79 and the shaft 42. The propeller 43 is provided with a hub 43', which hub is formed with an opening corresponding to the exterior shape of the housing 60, and at any rate secured to said housing for rotating therewith.

The rod 38 extends to the bearing element 40, which latter comprises a pair of spaced plates 84—84, a pair of studs 85 and 86 serving to space said plates and being secured by riveting in one of the plates and by nuts 87 in the other of said plates. The stud 86 receives a sleeve 88 having a threaded extension 89 for reception in the adjacent end of the rod 38.

As will be seen in Figure 9, the strap 32 is secured to the side-wall 25 by machine screws 35' and the plates 84 are secured to

said strap by transverse screws 90—90. The plates 84 are each provided with a complemental longitudinal slot 91 in which the free ends 92—92 of a transverse shaft 94 lie, said shaft supporting a rotatable hub 70 93 on which the sprocket 47 is integrally formed, and said hub also supporting outer sprockets 95—95. The shaft 94 is adjustable longitudinally in the bearing 40 and is locked by washers 96—96 and retaining nuts 97—97 so that the tension of the chains trained over said sprocket may be varied as desired.

Upon reference to Figures 4, 10 and 12, the construction of the frames F and F' 80 may be seen, said frames embodying the adjustable central radius rods 98—98, and the convergent brace-bars 99—99, which latter are arranged above and below the radius rods. As best shown in Figure 10, the radius rods comprise tubular portions 100, internally threaded at both ends, as indicated at 101 and 102. A pair of threaded studs 103 extend radially from the inner projecting end of the housing 60, said studs being formed integrally with said housing, diametrically opposite, and receivable into the adjacent ends of the tubes 100. A sheathing or sleeve 104 surrounds the tube 100 and the opposite ends of said sleeve are split at 95 105, said sleeve being coextensive with the tube 100 and being secured against longitudinal or rotative movement thereon by a transverse wedge pin 106. The outer end of the tube 100 receives the threaded end 100 of a stud 107, which latter is formed by bending laterally the longitudinal shaft 108 on which one of the elevators E is mounted.

Divided clamps 109 surround the outer split portions of the sleeve 104, transverse 105 bolts 110 passing through said clamps and the outer ends of brace-bars 99, so as to maintain the sleeve and thus maintain the tube in adjusted position. Other divided clamps 111 also surround the sleeve at the 110 inner split portions thereof, said clamps 111 also surrounding the brace-bars 99. Thus the rigidity of the frames F and F' and their adjustment are maintained.

The shaft 108, (there being two of these shafts, one for each elevator) is provided on each end with a ball race 112 held by a shoulder 113, and a similar arrangement being installed at the other end of said shaft. A hub 114 surrounds the shaft 108, in spaced 120 relation thereto, and said hub carries an integral sprocket wheel 115, a chain 116 being trained over said sprocket and also over one of the sprockets 81 on the shaft 42. The outer end of the hub 114 is provided with a ball race 117, complemental to the race 112, and a series of balls 118 are arranged between said races. The hub also supports an annular channel 119, to the walls of which are secured wire spokes 130

120, said spokes supporting the rims 121—121, forming the skeleton of the elevators. The channels 119 are pinned at 122 to the hub 114, and the wire spokes are provided 5 because of their strength and the fact that they offer little resistance to the passage of air. From an inspection of Figures 3 and 10, it will be seen that the chains 116 and their respective sprockets are staggered, so 10 that they do not interfere in operation.

The construction of the elevators is best illustrated in Figures 5 to 7, inclusive, wherein substantially one-half of the circumference of the rims is encompassed by 15 a sheathing 123, of thin board, or of heavy prepared fabric, there being provided two layers, an inner and outer, 124 and 125, respectively, the inner layer being stretched across and secured to the rims 121 in any 20 suitable manner, the outer layer being stretched over and glued or otherwise securely attached to the inner layer. Circumferential straps 126—126 encircle the layers 124 and 125 about the rims 121 to further 25 secure the layers, the straps having their edges turned under at 127 to prevent fraying. Transverse marginal strips 128 engage the longitudinal margins of the layers, and rivets 129 serve to secure said strips. The 30 inner layer 124 is provided with a plurality of folds which afford spaced longitudinal vanes 130—130, projecting radially inward.

I provide means for transmitting power from the engine 20 to the propellers and 35 elevators or stabilizers, said means comprising a vertical power shaft 131, journaled at its lower end in the frame 18 and operatively connected by bevel gearing 132, to the engine crank shaft, the upper portion 40 of said shaft being journaled in a bearing carried by the cross brace 133. The upper end of the power shaft 131 is provided with a beveled pinion 134, meshing with a bevel gear 135, which latter is mounted on one 45 of a pair of power transmission shafts 136, said latter shafts being arranged in spaced parallel relation in the passageway 22, and rotatively mounted in bearing openings formed in the front and rear transverse 50 bars 137 and 138. An intermediate transverse bearing brace 139 is provided, which is secured to the side walls 24 and 25, said brace 139 having bearings 140—140 for the shafts 136.

55 Each of the shafts is provided with a pair of gears 137—138, the gears of each pair being of equal diameter and located near the extremities of their respective shafts, in fixed engagement therewith, and 60 in meshing engagement, thereby transmitting power from the transmission shaft connected to the power shaft to the other of said transmission shafts. Pairs of sprocket wheels 142—142 are provided at each end 65 of both of the shafts 136, in fixed engage-

ment therewith, the gears 137—138 being arranged between the units of said pairs of sprockets, said sprockets being in accurate alinement with the sprockets 95—95, hereinbefore referred to, and pairs of sprocket 70 chains 143—143 being trained over said sprocket wheels 95—95 and their complementary sprockets 142 on the shafts 136, the side walls 24 and 25 having each openings 144—144 therein for accommodating the 75 chains 143—143.

From the foregoing it will be seen that power is transmitted to the elevators E—E and to the propellers 43 and 44 in opposite directions, and the gearing is arranged to 80 impart movement thereto at the required speed. The power transmitting elements, such as the shafts 136, chains 143, 46, and 116, are all arranged in pairs, so that power is equally transmitted to all propellers and 85 to both ends of the pairs of elevators, and thus dragging of one propeller relative to the others twisting of the elevators cannot occur.

It will be observed that the elevators and 90 propellers are so relatively disposed in each unit that the propellers serve to set up a current or currents of air through the elevating planes, the arrows X and Y indicating the direction of rotation of the planes, 95 and as these planes always maintain the same positions relative the longitudinal axis of the whole device, due to the fact that while they revolve about the shafts 42, they are maintained with their concavities toward 100 the bottom of the device by means of the sprockets 81, chains 116 and sprockets 115, the elevators always tend, during down strokes, to exert a downward pressure on the surrounding atmosphere, and thus stabilize 105 as well as cause the machine to rise. The vanes 130 on the under surfaces of the planes serve to impinge the currents of air set up by the propellers and thus the tendency to 110 sustain the device is maintained in flight; furthermore, the propellers serve to propel the machine. The formation of the planes embodied in the elevators also act, when necessary, somewhat in the nature of a parachute, so that volplaning or sliding with the 115 engine shut off is permissible.

In the form of the invention described hereinbefore, the operation of the device as a unit in itself is set forth, and as further 120 indicative of additional applications of this invention, reference may be had to Figures 13, 14 and 15.

Referring to Figure 13, there is illustrated a sea plane or flying boat, the hull H being 125 of any approved structure and containing the pilot's seat, controls, and a source of power, such as an internal combustion engine 145. A plurality of rows of struts 146 and 147 extend upwardly from the sides of 130 the hull H and serve to support the planes

148—148, 149—149 and 150. The planes 148 are at the same level and extend athwartships, the planes 149 being at a higher level and the plane 150 at a still higher level, the rear and forward edges of the forward and rear planes of each pair 148 and 149 being in the same plane vertically, and the plane 150 being of a length fore and aft coincident with the distance between the planes 149—149. In his way the planes appear as seen in Figure 14, and function as a safety measure in the event of failure of the engine while in flight.

The propelling and stabilizing devices illustrated in Figures 1 to 12, inclusive, and described hereinbefore, are employed in pairs here, that is, two units 151 and 152 are installed at approximately the level of the planes 149—149, directly below the plane 150.

Figures 14 and 15 illustrate the arrangement of planes of Figure 13, the gas bags 153 serving to convert the machine into a dirigible balloon, said gas bags being made fast to the structure shown in Figure 13 by means of suspending wires 154. Thus in the forms of the invention shown in Figures 13 to 15, inclusive, provision is made for propulsion of the machine, and also for safety in the event that the source of power fails. The arrangement of the planes 148, 149 and 150 will serve to prevent the machine from dropping, if kept level, and the elements E—E will aid the planes in this function.

36 While a specific structural arrangement has been illustrated, it will be understood that minor changes may be made within the spirit of the invention and scope of the claims.

40 I claim:

1. In a device of the character described, in combination, a pair of semi-cylindrical planes revoluble in a circular path but maintaining a parallel relation to a horizontal plane, an axis for said planes equidistant therefrom, and a propeller adapted to direct a current of air through said planes, said propeller being mounted on said axis.

50 2. In a device of the character described, in combination, a pair of semi-cylindrical planes revoluble in a circular path, an axis for said planes equidistant therefrom, a propeller mounted upon said axis and adapted to direct currents of air past said planes parallel to their respective axes, and means on said planes against which said air currents may impinge.

60 3. In a device of the character described, in combination, a pair of semi-cylindrical planes revoluble in a circular path, an axis for said planes equidistant therefrom, a propeller mounted upon said axis and adapted to direct currents of air past said planes parallel to their respective axes, and

longitudinal vanes for impinging said air currents.

4. In a device of the character described, in combination, a pair of semi-cylindrical planes revoluble in a circular path, an axis 70 for said planes equidistant therefrom, a propeller mounted upon said axis and adapted to direct currents of air past said planes parallel to their respective axes, and a plurality of internal vanes on said planes for 75 impinging said air currents.

5. In a device of the character described, in combination, equally spaced semi-cylindrical planes, said planes being mounted on shafts movable through a fixed circular path 80 about an axis, air propelling means on said axis directing air currents into and through said planes, and a plurality of longitudinal internal vanes on said planes.

6. In a device of the character described, in combination, an elevating device comprising a pair of half-cylinders opening downwardly, said cylinders being movable about a common axis, longitudinal internal vanes on said half-cylinders, and means for maintaining said cylinders with their vanes 85 in fixed relation to a horizontal plane.

7. In a device of the character described, in combination, an elevating device comprising a pair of half-cylinders opening 95 downwardly, said cylinders being movable about a common axis, longitudinal internal vanes on said half-cylinders, means for directing a current of air through said half-cylinders and past said vanes, a means operatively connected with first said means 100 for maintaining said cylinders during movement in fixed relation to a horizontal plane.

8. In a device of the character described, in combination, a pair of half-cylinders 105 mounted upon shafts, a nonrevoluble central shaft spaced equi-distant from first said shafts, means for moving said first shafts in a circular path around said nonrevoluble shaft, and means for maintaining said half-cylinders in fixed relation to a horizontal plane.

9. In a device of the character described, in combination, a pair of half-cylinders 115 mounted upon shafts, a nonrevoluble central shaft spaced equi-distant from first said shafts, means for moving said first shafts in a circular path around said nonrevoluble shaft, and means for rotating said 120 half-cylinders oppositely on their respective shafts and for preventing rotative movement of the cylinders relative to a horizontal plane.

10. In a device of the character described, 125 in combination, a supporting means, a stationary central shaft, frames rotatable on said shaft, curved planes carried by said frames, and propellers rotatable on the free ends of said central shaft.

11. In a device of the character described, in combination, a supporting means, a stationary central shaft, frames rotatable on said shaft, curved planes carried by said frames, means for rotating said frames, and propellers on the free ends of said central shaft for setting up currents of air through said planes.
12. In a device of the character described, in combination, a supporting means, a stationary central shaft, frames rotatable on said shaft, curved planes carried by said frames, means for imparting rotative motion to said frames, propellers on said central shaft, and means operatively connecting said propellers with said motion imparting means.
13. In a device of the character described, in combination, a supporting means, a stationary central shaft, frames rotatable on said shaft, curved planes carried by said frames, means for imparting rotative motion to said frames, propellers on said central shaft, means for operatively connecting said propellers with said motion imparting means, and means for driving said propellers, and the planes carried by said frames.
14. In a device of the character described, in combination, a supporting frame, a pair of stationary shafts on either side of said frame, a plurality of frames rotatively mounted on said shafts, a plurality of pairs of planes carried by said rotative frames and arranged on opposite sides of said stationary shafts, a plurality of propellers revolvable on said shafts, and means for simultaneously driving all of said planes and propellers about said stationary shafts.
15. In a device of the character described, in combination, a stationary shaft, a housing rotatable upon said shaft, a stationary bearing for supporting said shaft, and a driving sprocket on one end of said housing within said bearing.
16. In a device of the character described, in combination, a stationary shaft, a housing rotatable upon said shaft, a stationary bearing for supporting said shaft, and a driving sprocket upon the end of said housing in said bearing.
17. In a device of the character described, in combination, a stationary shaft, a housing rotatable upon said shaft, a stationary bearing for supporting said shaft, radially disposed and adjustable frames carried by one end of said housing, and a driving sprocket on the opposite end of said housing within said bearing.
18. In a device of the character described, in combination, a stationary shaft, a housing rotatable upon said shaft, a stationary bearing for supporting said shaft, radially disposed and adjustable frames carried by one end of said housing, rotatable elements carried by the outer ends of said frames, a driving sprocket on one end of said housing, and means operatively connecting said rotatable elements with said stationary shaft.
19. In a device of the character described, in combination, a stationary shaft, a housing rotatable upon said shaft, a stationary bearing for supporting said shaft, radially disposed and adjustable frames carried by one end of said housing, rotatable elements carried by the outer ends of said frames, a driving sprocket on one end of said housing, and stationary means on said stationary shaft and connected with said rotatable elements for imparting rotation thereto.
20. In an aeronautical device, a plane comprising a cylindrical frame, a semi-cylindrical fabric covering for said frame, and a plurality of spaced longitudinal ribs internally arranged on said plane.
- In testimony whereof, I affix my signature in the presence of two witnesses at 36 W. Randolph St., Chicago, Illinois.

ISRAEL I. ZIPERSTEIN.
